DESIGN FOR A BICYCLE FRAME

William H. Walker, Glendale, Calif., assignor to
American Brazed Products, Los Angeles, Calif.,
a corporation of California

Application June 28, 1946, Serial No. 131,122

Term of patent 7 years

(Cl. D90—8)

To all whom it may concern:

Be it known that I, William H. Walker, a citizen of the United States, residing in the city of Glendale, county of Los Angeles, State of California, have invented a new, original, and ornamental Design for a Bicycle Frame, of which the following is a specification, reference being had to the accompanying drawing, forming a part thereof.

Fig. 1 is a side elevation of a bicycle frame, showing my new design.

Fig. 2 is a plan view of a bicycle frame illustrated in Fig. 1.

Fig. 3 is a rear elevation of the frame illustrated in Figs. 1 and 2.

I claim:

The ornamental design for a bicycle frame, as shown.

WILLIAM H. WALKER.
